UNITED STATES PATENT OFFICE.

CHARLES W. SAALBURG, OF NEW YORK, N. Y., ASSIGNOR TO THE PRISMATONE CO., INC., OF NEW YORK, N. Y., A CORPORATION OF NEW YORK.

PROCESS FOR REPRODUCING PICTURES.

1,407,301.

Specification of Letters Patent. Patented Feb. 21, 1922.

No Drawing.

Application filed February 15, 1921. Serial No. 445,179.

To all whom it may concern:

Be it known that I, CHARLES W. SAALBURG, a citizen of the United States, residing at New York city, in the county of New York and State of New York, have invented a certain new and useful Improvement in Processes for Reproducing Pictures, of which the following is a specification.

My invention relates particularly to a process of reproducing pictures of various kinds, and for many different purposes.

The object of my invention is to provide a process by means of which pictures may be reproduced in quantity with very great rapidity and at a minimum cost. A further object is to provide a process of this character by means of which pictures may be reproduced, if desired, without necessitating the use of photography with the delays, cost, and inaccuracy of reproduction which are incident thereto. Again, one of the most important objects of my invention is to reproduce pictures by a method involving the use of etching, but which obviates the necessity of using sensitized sheets of paper for transferring the picture to the surface to be etched, so as to thus avoid inaccuracies in positioning, as for example, inaccuracies in registry in multi-color printing. The object of my invention is particularly to avoid the inaccuracies in registry due to shrinkage, stretching, and warping present in the use of sensitized sheets of paper, which must be made alternately wet and dry in order to carry out the processes previously in use. Again, another object is to provide instrumentalities which have better wearing and printing qualities than in the case of previous processes. Still another object is to provide such instrumentalities which have inked recesses thereon having different sizes and shapes, but of substantially the same depth.

Further objects of my invention will appear from the detailed description thereof set forth hereinafter.

While my invention is capable of embodiment in many different forms, for the purpose of illustration I shall describe only certain ways of carrying out the same hereininafter.

For example, in carrying out my invention, I may proceed as follows:

It will be assumed that the process is being used for producing multi-color pictures, but it is to be understood also that the

process is equally applicable for the production of pictures in one color, as for example black. In order to produce the multi-color pictures, I proceed as follows: A key roll or master roll made of copper or any other suitable material is provided with an etched impression in any suitable manner. This may be done in accordance with the previously known processes for producing rotary photogravure pictures, as when it is desired to produce in fine detail photographic subjects of various kinds. Said impression may be applied to the key roll, however, without the use of photography. In order to apply the impression in this manner, the roll is first coated with a suitable solution which may, for example, be comprised as follows:

5% by weight of vaseline,
15% " " asphaltum solution,
30% " " bees wax,
3% " " oil of lavender,
5% " " mastic varnish.

The asphaltum solution may be comprised of an amount of those constituents dissolved in an amount of turpentine to give the consistency of a thick cream, and so that it flows evenly. The mastic varnish may be comprised of mastic dissolved in turpentine to the consistency of a thick cream. This solution is applied to the cylinder while the latter is hot, and is allowed to drain and cool so as to cover the entire surface of the cylinder with a readily removable solid coating. Thereupon, I apply over the surface of the cylinder a thin sheet, which may, for example, be of very thin metal, such as aluminum, zinc, or tin, or which may be of transparent celluloid, or of paper, but which is preferably of a flexible unstretchable character. This sheet is previously prepared by roughening the upper surface thereof, as for example by rubbing the same with powdered glass or sand, or in any other manner, and on the under surface of the same either provided with a roughened surface or "tooth," by rubbing the same in a similar manner or in any other desired way, or instead, I may glue to said under surface a layer of some material having a rough surface, as for example crêpe de chine, Chinese muslin, or thin veiling, and which is preferably of a thin light character. The sheet having the surfaces thereon prepared in this manner is then bent over the coated surface of the key roll, and the edges of the

100
105
110

sheet are secured to the roll temporarily with adhesive tape.

The artist now draws upon the sheet, as for example with a pencil, the picture to be reproduced. The drawing by the artist upon the upper surface can be seen because the latter has been roughened. The artist also makes registry marks at the edges of the drawing which become transferred to the roll together with the picture drawn. The lines thus made cause the portions of the crêpe de chine beneath the sheet to remove the coating immediately beneath the same, opposite the places where the lines, dots, or other marks are drawn, so as to make corresponding lines, dots, or other marks in the coating, such lines being made, however, in the form of a group of dots located very close together because of the rough texture of the crêpe de chine. At the points where these lines, dots, or other marks are made, the surface of the copper roll is entirely uncovered, because of the coating having been removed by the pressure of the artist's pencil, so as to leave the same bare. When the picture has been completed in this manner, the sheet and the crêpe de chine attached thereto are removed from the cylinder, and the cylinder is then rotated in an etching bath of ferric chloride in water having a strength of 30 to 37 degrees Bé., until the desired depth of the etching is obtained. The roll is then washed with water, dried, and then subjected to a washing of turpentine to remove the remaining coating. An impression will now be found upon the roll corresponding to the picture drawn on the sheet comprised of innumerable dots of varying areas and shapes, but of the same depth.

In case the process is applied to the reproduction of fine photographic subjects, there will be no sheet used here as above indicated in producing the key roll, and in this event, no sheet is used for making the key roll, but said roll is made by photogravure in accordance with the methods of making such rolls previously used.

From this master roll are made a plurality of color printing rolls depending upon the number of colors to be used in making the particular picture. Such colors may be, for example, red, yellow and blue.

The key roll having been provided with positioning marks, as above described, near the four edges of the impression of the picture to be reproduced, the etched parts of said roll are supplied with an ink, pigment, or powder, as for example printer's ink dusted over with dragon's blood, and an impression is then made from this cylinder upon another unetched copper cylinder to form a guide upon the first of the color cylinders, as for example for printing in red. A sheet is now prepared for each of the

color rolls by printing on another sheet of the same character above described, an impression of the drawing from the key cylinder together with the registry marks thereon. The registry marks at the edge of the picture on the sheet will be cut out in case the sheet is made of an opaque material, so that they may be registered with the marks on the color cylinders which receive their initial impressions from the key roll. Said sheet is now applied to the first color cylinder by registering the marks referred to, and securing the edges of the sheet to the cylinder with adhesive tape, said cylinder having previously been supplied with a coating of a coating composition of the character above referred to, and in the manner above described. The artist now draws upon the surface of said sheet a drawing with the necessary technique for the parts of the picture to appear in red, and these portions of the picture become thus transferred to the cylinder as above indicated. The plate and attached fabric are then removed, the cylinder etched, washed, dried, and treated to remove the coating composition in the same manner as above described.

Where it is desired to show in the picture delicate fine tones, such as the sky and flesh tints, the color roll may be subjected to a further treatment of the following character: The drawing by the artist which has already been applied as above described supplies to the picture the masses and important parts thereof, but the remainder of the picture comprising the delicate fine tones is supplied in a different way. In order to accomplish this, the roll has wiped thereon a thick ink, so as to fill the crevices of the etching, and the surface is then rubbed absolutely clean with a rag and the hand, and the ink is dried upon the roll by heating. Thereupon, the roll has applied thereto a thick asphaltum varnish diluted with turpentine, by means of an air brush which has the effect of producing on the surface of the roll a multitude of fine particles or droplets of the composition thus applied in the form of a delicate spray. This asphaltum varnish will be comprised of asphaltum, or any resinous material dissolved in turpentine to a consistency suitable for the air brush or spraying. The effect will be to provide a miniature grain upon the surface, the size of which will depend upon the distance of the spray away from the surface. The greater the distance, the finer will be the spray and the resultant grain. The particles of the resinous composition will then harden upon the roll due to the evaporation.

If desired, instead of applying the asphaltum in this manner, a grain may be made upon the surface of the roll by heating the same, allowing particles of a dried powdered resin, such as rosin, to fall upon the surface

thereof while rotating, heating the roll to melt the grains to cause the same to adhere thereto, and spreading the grains somewhat by later applying a higher heat. The first 5 described method by using an air brush is, however, preferable.

After this has been done, and the grain has been thus applied to the roll and allowed to harden, the masses and important parts 10 of the picture are blocked out by applying to these portions of the picture a mastic varnish, made as above, or other varnish, so as to prevent these portions of the picture from becoming etched. Where portions of 15 the picture are to be blended or shaded off gradually, this may be accomplished by applying to the edges of the blocked out portions, a lithographic wax crayon, the same as is used on lithographic stones. After the 20 roll has been prepared in this manner, it is etched slightly with a bath of ferric chloride of the same character previously described, is washed and then dried. If desired, to provide variations even in these delicate fine 25 tones, portions may now be blocked out in a similar manner and the etching continued in the same way. This may be repeated several times, if desired, until the artist is entirely 30 satisfied. Thereupon, all of the materials 35 on the roll are removed by the application of gasoline or turpentine, and the roll thus prepared is ready for printing. For printing, the roll is provided with any suitable ink applied in any suitable way, and in fact 40 may be operated and manipulated the same as in the case of rolls used in rotary photogravure in accordance with the previous processes.

When pictures are produced from these 45 color rolls, it will be found that perfect registry is obtained, as the pictures have in effect been made by combining impressions from several cylinders which register exactly with the key cylinder. Where the key 50 cylinder is used to make all of the other impressions on the other cylinders, it is not possible for the impressions on said other cylinders not to occupy the same relative positions, as would be the case if from a single subject a number of photographic 55 sensitive sheets of paper should be needed for transferring the several colors of the picture to different cylinders.

While I have described my invention above 60 in detail, I wish it to be understood that many changes may be made therein without departing from the spirit thereof.

I claim:

1. The process of etching a master cylinder or roll comprising applying a coating of a material capable of removal by a slight pressure, fixing thereover a thin sheet of material having a rough rear surface, drawing a design and registry marks upon the sheet 65 whereby corresponding parts of the said

coating are removed, and etching the cylinder.

2. The process of etching a master roll comprising applying a coating of an asphaltum composition capable of removal by 70 a slight pressure, fixing thereover a thin sheet of paper having a rough rear surface, drawing a design and registry marks upon the sheet whereby corresponding parts of the said coating are removed, and etching 75 the cylinder.

3. The process of etching rolls to secure registry, comprising the steps of transferring to a roll a design containing registry marks from a master roll, supplying the 80 former roll with a removable coating, removing portions of the coating to register with the design to be printed in color, etching the rolls, and removing the coatings.

4. The process of etching rolls to secure 85 registry, comprising the steps of transferring to color rolls a design containing registry marks from a master roll, supplying the color rolls with removable coatings, securing thereon in registry thin sheets having 90 impressions of the design, drawing the color design on the sheets, etching the rolls, and removing the coatings.

5. The process of etching rolls to secure 95 registry, comprising the steps of transferring to color rolls a design from a master or key roll provided with registry marks, printing thin papers having rough rear surfaces from the key roll, placing them in 100 registry on the color rolls prepared by coating them with a removable coating, drawing the color design on the paper, etching the color rolls, and finally removing the coatings.

6. The process of etching copper rolls to 105 register in color work, comprising the steps of transferring to color rolls a design containing registry marks from a key roll, supplying the color rolls with removable coatings, removing portions of the coatings by 110 pressure through a registering paper print of the key roll, said portions registering with the design to be in color, etching the rolls, and removing the coatings.

7. The process of etching rolls to register 115 in color work, comprising the steps of transferring to color rolls a design from a key roll having registry marks, printing thin papers having rough rear surfaces from the key roll, placing them in registry on color rolls 120 coated with a removable coating, drawing the color design on the paper, etching the color rolls, and finally removing the coatings.

8. The process of etching rolls to secure 125 registry, comprising the steps of etching a master roll in a design having registry marks, supplying the etched parts with a pigment, making an impression therefrom upon another or color roll, printing a sheet from the master roll, coating the color roll, 130

supplying thereon in registry the printed sheet, drawing thereon the design to be in color, and etching the color roll.

9. The process of etching a color roll to produce designs adapted to yield fine tones, comprising etching the principal design in the color roll, applying and drying a thick ink within the etched portions, applying a thick asphaltum varnish spray on the surface of the roll, blocking out portions of the design, and then etching to produce the fine tones.

10. The process of etching a color roll to produce designs adapted to yield fine tones, comprising etching the principal design in

the color roll, filling in the etched portions, applying a spray over the surface of the roll, blocking out portions of the design, and then etching.

11. The process of etching a color roll to produce designs adapted to yield fine tones comprising etching the principal design in the color roll, filling in the etched portions, applying a fine grain over the surface of the roll, blocking out portions of the design, and then etching.

In testimony that I claim the foregoing, I have hereunto set my hand this 11th day of February, 1921.

CHARLES W. SAALBURG.
